UNITED STATES PATENT OFFICE.

MICHAEL A. CHINCHILLA, OF PHILADELPHIA, PENNSYLVANIA.

DESIGN FOR A COMBINATION MIRROR FRAMES AND SHELVES.

Application filed December 13, 1927. Serial No. 24,460. Term of patent 14 years.

To all whom it may concern:

Be it known that MICHAEL A. CHINCHILLA, a citizen of the United States, residing in Philadelphia, county of Philadelphia, and the State of Pennsylvania, has invented a new, original, and ornamental Design for Combination Mirror Frames and Shelves, of which the following is a specification, reference being had to the accompanying drawings, forming a part thereof.

Figure 1 is a view in front elevation of a

combination mirror frames and shelves, showing the new design.

Figure 2 is an end view also showing the new design.

Figure 3 is a perspective view showing the new design.

What is claimed is:

The ornamental design for a combination mirror frames and shelves as shown.

MICHAEL A. CHINCHILLA.
